UNITED STATES PATENT OFFICE

2,260,830

START-UP DEVICE FOR ROLL CHANGERS

Allan J. Cline, Chicago, Ill.

Application March 9, 1938, Serial No. 194,908

18 Claims. (Cl. 242—58)

This invention relates to web roll changing apparatus employed in connection with printing presses for connecting the web of an expiring roll to that of a full roll, and more particularly to a device for starting rotation of the full roll preparatory to making a "paster" between the new and old webs whereby the feed may be changed from one roll to the other without stopping the press.

In accordance with the usual practice, the new or reserve roll is prepared for the making of a paster by placing glue or other suitable adhesive on the surface of the roll near the end of the web which is releasably attached to the body of the roll by a frangible tab, or in other suitable manner, so that when the adhesive comes in contact with the running web the new web is attached to the old, the latter being then severed by a suitable cut-off device and the supply of paper thereafter continuing from the new roll. Inasmuch as the adhesive is ordinarily in a moist condition it must not contact the running web until the surface speed of the new roll approximately equals that of the running web. Consequently, in some types of roll changing apparatus complicated mechanism is provided for rotating the roll from the spindle on which it is mounted so that it can be rotated a number of times before being brought into contact with the expiring web. In other forms of roll changers it has been necessary to start rotation of the roll by hand and through the action of the running web thereon after the new roll has been brought into contact with said web, it being obvious that in such case the roll can only rotate a partial revolution before the paster is made and the speed of the web, and consequently of the press, must be accommodated to the speed which can be obtained in a partial revolution of the roll. My invention relates to a mechanical device for giving a powerful rotative impulse to the roll to overcome the inertia thereof and bring it up to a substantial speed in considerably less than one revolution, after which the action of the running web thereon brings it up to its linear speed before the revolution is completed, thus making it possible to effect successful pasters without greatly, if at all, slowing down the press.

It is an object of the invention to provide a device of this character which is efficient and largely automatic in action and which is usable effectively under ordinary conditions prevailing in a newspaper plant without requiring extraordinary skill on the part of the workmen who

are responsible for operation of the roll changing apparatus.

A further object of the invention is the provision of a device for the purpose stated, which acts upon the end of the roll which is an accessible and practical place for the rotative force to be applied.

Another object of the invention is the provision of a device of this character which can be readily applied to the ordinary press sub-structure and adjusted to operate in connection with rolls of different length.

Still another object of the invention is to provide a roll starting device which can be brought into contact with the roll and released therefrom by manual control under certain conditions but which, when the paster operation is in progress, will be automatically maintained in contact with the roll and will be released therefrom at exactly the right time after the roll has been brought to desired speed.

A further object is the provision of a roll starting mechanism which is automatically controlled and caused to operate by movement of the new roll into the web proceeding from the expiring roll.

In the preferred embodiment of the invention shown in the drawings compressed air is employed as the motive force for actuating the roll propelling mechanism and also for moving the roll engaging element into contact with the roll and maintaining the contact during the positive portion of the operating cycle.

A further object of the invention is to provide an efficient valve controlling mechanism designed to admit the air to the parts controlled thereby and to release the same at the exact time required, the control being to a considerable extent automatic and the several control elements being so coordinated as to effectively obtain the desired results.

The roll engaging element of the device is so mounted and its movement so controlled that it is held in engagement with a particular point on the end of the roll during the period of contact and there will be little or no tendency for said element to slide off the arc of rotation of said point.

Other objects and advantages of the invention will be apparent from the following detailed description, taken in connection with the accompanying drawings wherein I have shown the preferred form in which I have thus far contemplated applying the principles of the invention.

Referring to the drawings:

Fig. 1 is a view partially in section taken from one end of a reel on which three web rolls are adapted to be mounted in the usual manner, the device of my invention being shown in side elevation;

Fig. 2 is an enlarged detail view of a fragment of one end of one of the reel arms shown in Fig. 1, and fragments of the mechanism adapted to be operated by an operating finger or projection carried by each of the reel arms;

Fig. 3 is an elevational view of the reel structure and associated parts being taken transversely through the press sub-structure and being partially broken away for the sake of compactness;

Fig. 4 is an enlarged detail view showing a portion of the manual valve control mechanism;

Fig. 5 is a plan view of the major portion of the roll starting mechanism of my invention;

Fig. 6 is a side elevation of the mechanism shown in Fig. 5, certain parts being shown in section;

Fig. 7 is a longitudinal sectional view of the pneumatic drive for the starting mechanism;

Fig. 8 is an enlarged sectional view of the roll contacting element and associated parts taken substantially on the section line 8—8 of Fig. 6;

Fig. 9 is a plan view of the starting mechanism, being shown in reverse position from that shown in Fig. 5 and illustrating certain additional parts;

Fig. 10 is a side elevation of the mechanism shown in Fig. 9, said mechanism being viewed from the side opposite that shown in Fig. 6;

Fig. 11 is an end elevation of the pneumatic drive unit showing the cylinder head and the associated conduits and valve mechanism;

Fig. 12 is an enlarged transverse sectional view of one end of the starter carriage taken substantially on the section line 12—12 of Fig. 6;

Fig. 13 is a plan view of the operating mechanism for certain of the valves employed in the device;

Fig. 14 is a side elevation of the same; and

Fig. 15 is a detail view of certain parts shown in Fig. 13, showing the position of said parts when the starter crosshead is in its extreme advanced position.

The illustrative embodiment of the invention shown in the drawings comprises an adjustably mounted unit 21 supported in cross supporting members 22 positioned beneath the press frame 23 and upon arms 24 and 25, respectively, formed upon frame uprights 26 comprising parts of the press sub-structure.

Web supporting reels are mounted in said sub-structure and comprise a center shaft 27, on the opposite ends of which are mounted spiders 28, each formed to provide three roll supporting arms 29 adapted to support web rolls identified, respectively, by the numerals 31, 32 and 33. Each roll is supported between corresponding opposed arms of the respective spiders, being held in place by means of chucks 34 extending into hollow shafts or spindles extending through the center of the rolls, said chucks being locked in place to rotatably support the rolls in a manner which is well known in the art. The reel is adapted to be rotated to change the position of the reel arms and the rolls carried thereby by means of a motor and gear mechanism mounted in housings 35, 36 and 37 shown in Fig. 3 of the drawings. As shown in Fig. 1, the web 38 is being drawn into the press from the roll 31 which has nearly expired, said web extending over rollers 39 and 41 around a floating roller 42 carried by arms 43 pivotally mounted upon a shaft 75

44, the web proceeding upwardly from the floating roller 42 into engagement with a guide roller 45 and thence into the press.

A tension strap 46 is mounted to contact with the active roll to control the speed of rotation thereof, said strap being anchored at its lower end to spring bolts 47 positioned in a pit or other suitable location beneath the reel and at its other end extends around a wind-up cam 48 mounted on a cam shaft 49, said tension strap, of which there may be several across the width of the roll, having brush sections 51 against which the pasters are made in a manner which will hereinafter appear. The normal running position of the active roll 31 is indicated in dotted lines in Fig. 1, as are the normal positions of the rolls 32 and 33. In making a paster the reel is rotated to bring the rolls to the full line positions shown in Fig. 1, in which positions, as will be noted, the reserve roll 32 is moved against the web 38, bowing the latter outwardly and pressing the same against the tension straps 46, as will hereinafter appear.

A cut-off device generally indicated by the reference numeral 50 is provided for severing the web of the expiring roll after the paster has been made. While any suitable or preferred cut-off mechanism may be employed for this purpose, reference may be made to Patent No. 2,086,068 for a disclosure of a satisfactory cut-off mechanism.

The roll starting mechanism is mounted in a carriage 52 comprising spaced ways 53 secured by screws 54 to spaced brackets 55, each of which has a T-shaped head 56 carrying two pairs of rollers 57 disposed between pairs of channel members comprising the cross supports 22, the lower flanges 58 of said channel members serving as rails upon which the rollers 57 travel when the carriage is adjusted toward or away from the web roll. Each bracket portion 56 is provided with an ear 59 apertured to receive a locking pin 61 extending through registering openings 62 in the channel members of the cross supports 22.

Said roll starting mechanism includes a cross-head, indicated generally by the numeral 63, slidably mounted in the carriage 52, a pneumatic drive unit indicated generally by the numeral 64, fixedly mounted in one end of said carriage, and a roll engaging unit 65 carried by the cross-head 63.

The crosshead assembly is illustrated in detail in Figs. 5, 6, 9 and 12. Referring first to Fig. 10, it will be observed that the crosshead comprises a casting 66 which is roughly rectangular in shape and is disposed in a vertical plane between the ways 53 and the ends of the rolls 31, 32, 33.

Mounted in bosses 67 formed in the casting 66 near its four corners, respectively, are studs 68 on which are journaled rollers 69 (see Figs. 6 and 12). The rollers 69 are rollingly engaged between the opposed faces of rail flanges 71 formed in the ways 53, whereby the crosshead 63 is supported by the ways for traveling movement longitudinally thereof. The horizontal counter-thrust of the roll engaging unit 65 against the crosshead 63 when exerting pressure against the end of the roll 32, is sustained by the rolling engagement against the vertical faces of the ways 53, of rollers 72 mounted on studs 73 that are fixed in vertical bosses 74 forming the ends of the crosshead casting 66. When the roll engaging unit 65 is not in operation, the cross-head is maintained in position relative to the

ways 53 by vertical bars 75, secured by screws 76 to the ends of the studs 73, the ends of the bars 75 being slidably engaged against the faces of the rail flanges 71 opposite the rollers 72.

The roll engaging unit 65 comprises an arm 77 (see Figs. 10 and 12) pivoted at one end upon a horizontal stud 78 mounted in a boss 79 formed on the crosshead casting 66, so that it may swing vertically. Near its free end, the arm 77 is formed with a transverse cylinder 81 in which is mounted a piston 82 (see Fig. 8) having in its head a depression defined by an annular flange 83. A circular pad 84 of resilient material, such as soft rubber, mounted in the depression, serves to frictionally engage the end of the roll 32.

The vertical swinging of the arm 77 allows the pad 84, while in engagement with the end of the roll 32, to describe an arc of movement coaxial with the axis of the roll while the crosshead 63 moves horizontally. In order that the pad may follow the changing inclination of the radius of the roll on which it is engaged, the piston 82 is rotatable in the cylinder 81. Thus the pad 84 may remain in fixed engagement with the roll during the entire period of contact.

Referring particularly to Figs. 9 and 10, it will be seen that rollers 85 mounted on studs 86 fixed in bosses 86' formed on the crosshead casting 66 on axes that are radial with respect to the arm pivot 78, serve to sustain the counter thrust of the arm 77 under pressure of the pad 84 against the roll 32 while allowing the arm 77 to freely swing vertically, said rollers being engaged by an arcuate end portion 90 on the arm 77.

In order to avoid any tendency of the pad to slide off its arc of movement during the starting impulse it is important that in locking the pad against the roll it engage the roll each time at the same distance from the roll axis. But it is possible to lock the pad against the roll in any of several positions of longitudinal movement of the crosshead, and the distance of the crosshead from the roll axis will vary with each of these positions. Accordingly, means is provided for supporting the arm 77, when the pad 84 is not engaged against the roll, in proper position for engagement with the roll, such means including an arcuate cam 87 (see Figs. 10 and 1), the ends of which are secured to the lower way 53, a roller 88 adapted to travel on the cam 87, and an arm 89 on one end of which the roller 88 is journaled by means of a stud 91 secured on the arm.

The other end of the arm 89 is curved at 92 around the pivoted end of the arm 77 and which is pivoted upon a stud 93 secured in an ear 94 formed on said arm 77.

A plunger 95 is secured at one end in a stud 96 pivoted in the arm 89 near the free end thereof. The other end of said plunger is slidably mounted in a boss 97 formed on the arm 77, and the medial region of the plunger passes through a coil spring 98 which is compressed between the stud 96 and the boss 97. The parts are so arranged that the roller 88, riding against the cam 87 as the crosshead moves longitudinally, will raise and lower the arm 89 so as to maintain the pad 84 approximately at a uniform distance from the axis of the roll 32 at all times when the pad is not engaged with the roll. When the pad is engaged with the roll, the arm 89 will be allowed to swing so as to conform to the arc of movement of the point where the pad is engaged, the spring 98 allowing said arm to yield upwardly relative to the arm 77, or the roller 88 lifting

off of the cam 87 whenever necessary to compensate for any variations that may occur between the curvature of the cam and the path of movement of said roller 88 which would correspond to the arc of movement of the pad 84. The upper end of the plunger 95 is secured against escape from the boss 97, by means of a head 99 on the plunger.

Referring now to Fig. 8, the cylinder 81 is closed behind the piston 82 by a cylinder head 101 secured to the cylinder by cap screws 102 (see Fig. 6). The central region of the head 101 is formed with a sleeve 103 which at its outer end is attached to an elbow 104. A nipple 105 connects the elbow 104 to a flexible tube 106 which communicates with a source of air under pressure. The piston 82 is provided with a piston rod 107 one end of which is rigidly secured in the central region of the piston. The rod 107 extends through the sleeve 103 and on its other end is secured an annular guide collar 108, slidably mounted in the bore of the sleeve 103 and secured to the outer end of the rod 107. A coil spring 109 is positioned in the sleeve 103 and engaged between the collar 108 and the inner end 111 of said sleeve 103. The piston rod 107 extends through the spring 109 and through an opening 112 in the end 111 of the sleeve.

The piston 82 has a skirt 113 of flexible material secured to its rear face by a clamping ring 114 and screws 115 extended through apertures in the ring and threaded into the piston. The skirt 113 serves to seal behind the piston the compressed air which is injected into the cylinder through the flexible tube 106. The air enters the cylinder through the sleeve 103, passing through openings 116 in the guide collar 108 and through openings 117 and the opening 112 in the inner end 111 of the sleeve 103. Under the pressure of air thus injected, the piston will move forwardly in the cylinder to bring the pad 84 into engagement with the end of the roll 32. The coil spring, which has been placed under compression by this advancing movement, will return the cylinder and pad to inoperative position when the air pressure is released.

The sleeve 103 extends through an opening 118 (Figs. 6 and 10) in the crosshead casting 66, and is adapted to contact, at the upper and lower limits of movement of the arm 77, a pair of resilient cushioning buffers 119 mounted in bosses 121 in the casting 66.

The other end of the tube 106, as shown in Figs. 6 and 10, is connected to a release valve 122 mounted in a bracket 123 on the crosshead casting 66 near the axis of the arm pivot 78 so that the tube 106 may flex as the arm 77 moves up and down in a region that is intersected by said axis. The release valve 122 serves, at the proper time, to release the air from the cylinder 64.

Referring now to Figs. 6 and 7, it will be noted that air reaches the tube 106 through a pipe line 123, one end of which is connected to the valve 122 through a return bend 124 and the other end of which is bent upwardly as at 125 and connected by means of an elbow 126 to a lateral passage 127 (see Fig. 7) formed in a boss 128 in the crosshead casting 66. The passage 127 communicates with a longitudinal passage 129 which in turn communicates with an opening 131 in an end member 132 of a tube 133 mounted at one end in the boss 128 in the end of the crosshead casting 66, the tube 133 extending into the main cylinder 64 of the pneumatic drive unit

previously described. It may be noted at this point that the tube 106, release valve 122 and pipe line 123 all move with and form part of the crosshead assembly. The tube 133 forms part of a telescoping air supply line connecting this movable crosshead assembly to the stationary portion of the air system.

The pneumatic drive includes the cylinder 64, mounted at its ends in the cylinder heads 134 and 135 which, as will be noted from Figs. 6 and 11, are clamped tightly against the ends of the cylinder 64 by tie rods 136 and nuts 137 threaded on the ends thereof, and are provided with ears 138 secured at 139 to the ways 53. In the cylinder 64 there is a piston generally indicated at 141, including a collar 142 into which the tube 133 is threaded, an annular flange 143 formed integrally with the collar 142, and cupped piston rings 144 of flexible material secured against the flange 143 by clamping rings 145 and screws 146. The tube 133 serves as a piston rod to transmit driving movement from the piston 141 to the crosshead 63 when air is introduced into the cylinder 64 between the piston 141 and the head 134. It also serves, as previously stated, as part of a telescoping air line for carrying air to the roll engaging unit, the other portion of said line being a smaller tube 147 threaded at 148 into a boss 149 in the head 134 and telescoping into the tube 133.

Where the tube 147 enters the tube 133, it is sealed with relation thereto by a packing gland comprising a washer 151 secured between the end of the tube 133 and an inturned flange 152 on the end of the collar 142, a ring of packing material 153 interposed between the two tubes, a wedging ring 154, and a coil spring 155 compressed between the ring 154 and a collar 156 mounted against a shoulder 157 in the tube 133. Thus air supplied to the tube 147 is prevented from entering the cylinder 64 and vice versa.

The tube 133 enters the cylinder 64 through a central opening 158 in the cylinder head 135, which is adapted to receive the forward end of the collar 142 as the piston approaches the end of its driving stroke. During the starting impulse, the piston 141 will expel the air in the cylinder 64 between said piston and the head 135, first through said opening 158, and, near the end of the stroke after the collar 142 has entered said opening 158, through a needle valve 159, which is adjustable by means of a cap screw 161 to vary the rate of release of the air, so that a proper quantity of air may be trapped in the cylinder to properly cushion the end of the piston stroke.

Referring now to Figs. 1, 5 and 11, the air supply for both cylinders is brought through a common supply line 162 leading to a T-union 163 located near the head 134. From the T-union 163, the line extends to the main cylinder through a union 164, a main control valve 165, an elbow 166, a nipple 167, and a passage 168 (see Fig. 7) in a boss 169 formed in the cylinder head 134.

The line for the cylinder 81 of the roll engaging unit branches laterally from the T-union 163 through a union 171 (Fig. 5), an elbow 172, a pipe section 173, a cut-off valve 174 located beneath the cylinder 64, an elbow 175, upwardly inclined pipe sections 176 joined by a union 177, an elbow 178 attached to a boss 179 formed in the head 134, a passage 181 formed in said boss 179, a passage 182 in the boss 149, and thence through the telescoping tubes 147 and 133, the

passages 129 and 127 in the boss 128 on the end of the crosshead casting 66, the line 123, valve 122 and tube 106.

Each of the valves 122, 165 and 174 includes an operating sleeve 183 (see Figs. 6 and 13), having an annular groove 184 for engagement by a fork of an operating lever, and is of a type well known in connection with air-brake equipment, being so designed that when its operating sleeve is moved in one direction air from the supply line is allowed to flow to the cylinder served thereby, and when said sleeve is moved in the opposite direction the supply of air is shut off the sleeve at the limit of movement in the latter direction establishing communication between the cylinder and the atmosphere so as to "bleed" the cylinder, i. e., release the air therefrom.

The valve 165 (see Fig. 13) is controlled by a rod 185 slidably mounted in brackets 186 secured to the lower side of the lower way 53 of the carriage 52. A bell crank lever 187, pivoted at 188 to a bracket 189 secured to the lower way 53, has a fork 191 engaged with the sleeve 183 of said valve 165, and a fork 192 engaged between spaced collars 193 secured on the rod 185. Said rod 185, when moved to the left as viewed in Fig. 13, will rock the bell crank lever 187 so as to move the operating sleeve 183 toward the cylinder 64 to establish communication between the air supply line and said cylinder.

The control rod 185 is operated by the movement of the reel arms 29, as the roll 32 is moved into the web 38. On the end of each arm 29 (see Fig. 2) there is secured, by screws 194, a bracket 195 to which is attached by screws 196 an operating finger 197 projecting radially with respect to the reel axis. On the rod 185 is a trigger arm 198 which has at one end a sleeve 199 through which the rod 185 extends, and by means of which the arm is slidably mounted on the rod between collars 201 and 202 fixed on the rod (see Fig. 14). A trigger finger 203, positioned to be engaged by the operating fingers 197, is pivoted at 204 on an ear 205 on the trigger arm 198 and adjustably associated therewith by engagement with an adjusting screw 206 threaded through the arm.

Movement of the trigger arm 198 under the engagement of the trigger finger 203 by the operating finger 197 on a reel arm 29 is transmitted to the rod 185 by a coil spring 207 positioned on said rod 185 and engaged between the collar 201 and the collar 199. The spring 207 provides for full opening of the valve 165 without injury to any of the parts.

Moving of the crosshead 63 to the retracted position shown in Fig. 1, is also effected by the operating fingers 197 on the reel arms. An arm 208 is pivoted near one end between a pair of ears 209 on the crosshead 66, on a pivot pin 211 (see Fig. 6), and is supported by the engagement of its upper end 212 with an adjusting screw 213 threaded through a boss 214 on the casting 66 in a position projecting diagonally downwardly into the path of movement of the fingers 197. Its free end is formed with a shoulder 215 defining one side of a notch 216 into which the finger 197 is adapted to move when the crosshead is at its extreme advanced position at the right end of the carriage 52 as viewed in Fig. 1. As the roll 32 is moved into the web 38, the engagement of the finger 197 with the shoulder 215 will carry the arm 208 and with it the crosshead 63 to the retracted position, said arm 208 yielding upwardly as the finger 197 swings upwardly,

and following downwardly as the finger swings past the peak of its arc. When the crosshead has reached the fully retracted position, the arc of movement of the operating finger 197 will pass below the level of the lower extremity of the shoulder 215 in the lowermost position of the arm 208 as determined by contact with the screw 213. Thereupon the cross head will be released.

A slight further movement of the reel will cause the finger 197 to engage the trigger finger 203, operating the valve 165 to inject compressed air into the cylinder 64 so as to cause the piston 141 and with it the crosshead 63 to be driven forcibly to the right.

The valve 174 (see Figs. 11 and 13) which is for the purpose of admitting air to the cylinder 81 of the roll engaging unit, is controlled by a rod 217 slidably mounted in certain of the brackets 186 behind the rod 185. A bell crank lever 218, similar in construction and arrangement to the lever 187, and associated parts, transmit movement of the rod 217 to the operating sleeve 183 of the valve 174 so that when the rod 217 is moved to the left, as viewed in Fig. 13, the valve 174 will be operated to admit air to the cylinder 81; while at the limit of movement of the rod 217 to the right the valve 174 will be operated to release air from said cylinder 81. Manipulation of the valve to either of these positions may be accomplished manually by a hand lever 219 (see Fig. 3) secured to one end of a square shaft 221. The other end of the shaft 221 is slidably extended through a squared opening in one end of an operating lever 222 (see Fig. 4). The shaft 221 is journaled in a bracket 223 secured to the frame 23 of the press adjacent the hand lever 219 and in a pair of spaced bearings 224 on the bracket 55 at the right end of the carriage 52 as viewed in Fig. 1. The shaft 221 extends under and parallel to the forward supporting rail 22, and, as the carriage 52 is adjusted beneath the rails 22, the operating lever 222 will be moved along the shaft 221 by the bearing 224.

Movement of the operating lever 222 caused by rotation of the shaft 221, is transmitted to the rod 217 by a fork 225 on the lower end of the lever, engaged between spaced collars 226 secured on the rod 217 (see Figs. 13 and 14).

Manual control of the valve 174 is supplemented by partial automatic control, provision for which is embodied in a trigger 227 pivoted at 228 to the lower side of the lower way 53 (see Figs. 13 and 14). The trigger 227 has an oval shaped central region engaged between two collars 229 slidably on the rod 217, and having an aperture extending from side to side, through which the rod 217 extends. The collars 229 are engaged between two coil springs 231 which in turn are confined between two collars 232 fixed on the rod 217. These springs assure movement of the valve control sleeve to its two extreme positions without injury to the parts. The trigger 227 has a wedge-shaped nose 233 adapted to be engaged by projections 234 and 235 extending laterally from legs 236 and 237 projecting downwardly from the crosshead casting 66. The projection 234 has a relatively wide engaging face, adapted to ride upon and remain in engagement with the nose 233 of the trigger 227 as shown in Fig. 15, while the projection 235 has a narrow engaging face and is adapted to deflect the trigger 227 in passing, in the direction of its movement.

In the position shown in Fig. 15, the crosshead is at its extreme advanced position at the right

end of the carriage 52. In this position, the engagement of the trigger 227 by the projection 234 holds the rod 217 in its extreme position to the right, maintaining the valve 174 in air-releasing position with the roll engaging pad 84 retracted, so that it is impossible for the operator to lock the pad against the roll. This assures the roll being free to rotate when there is occasion to manipulate it, as when the adhesive is being applied. By rotating the reel until the crosshead starts to be retracted, the trigger 227 is freed between the projections 234 and 235 so that the operator may lock the pad against the roll or release it at will, by manipulation of the valve 174.

This provision for manual control at this stage is important, since the operator will find it preferable to maintain the adhesive coated surface of the roll in a position about as indicated at 238 in Fig. 1, locking the pad against the roll to assure its remaining in that position, until he is ready to start the paster operation, when he will release the roll, rotate it until the pasted surface is at about the position indicated at 239 and then again lock the pad against the roll. The reason for maintaining the pasted surface at or near the point 238 is to avoid its being contacted by the web 38 in the event the latter breaks and drops downwardly onto the roll 32. It will be understood that the adhesive will be applied sufficiently in advance of the exhaustion of roll 31 to leave the operator plenty of time to effect the subsequent operations without being rushed.

When the paster operation is once started, however, the operation proceeds automatically. The electric motor mechanism, indicated generally at 35 to 37, when its circuit is closed by a control switch (not shown), causes the reel to revolve in a counter-clockwise direction, as viewed in Fig. 1, carrying the roll 32 into the web 38 and simultaneously retracting the crosshead 63. If the operator has not already locked the pad 84 against the roll, this will be automatically effected when the crosshead has been retracted a short distance by the engagement of the trigger 227 by the projection 235, moving said trigger to the left to the position shown in Fig. 13 and moving the rod 217 to the left, thereby operating the valve 174 to admit air to the cylinder 81.

The valve 122 serves to quickly release the pressure from the cylinder 81 just prior to the end of the forward or driving stroke of the crosshead. Unlike the valves 165 and 174 it is provided with a spring 241 which tends to move the operating sleeve 183 to air-releasing position. The sleeve is normally restrained from reaching this position, however, by a bell crank lever 242 pivoted at 243 on an ear 244 projecting from the crosshead casting 66, having at one end a fork 245 engaged with the sleeve 183 and at its other end a fork 246 in which is journaled a roller 247 which rides against the underside of the upper way 53 of the carriage 52. Just prior to the end of the driving stroke of the crosshead, the roller 247 will ride under an elongated opening 248 in the way 53, and, under the push of the spring 241, will move upwardly into said opening, pushing upwardly a block 249 pivoted intermediate its ends on a horizontal pin 251 traversing the opening, whereby the valve 122 will be opened to release the air from the cylinder 81. This position is shown in dotted lines in Fig. 10.

At the end of the driving stroke of the crosshead, the roller 247 will move past the pivot pin 251 and engage the other end of the block 249

so as to cause the block, which has a weight 250 on the top thereof, to resume its full line position in which its lower face is flush with the lower surface of the way 53, and simultaneously a latching bar 252, longitudinally slideable in yokes 253 on the upper face of the way 53, will be moved to a position projecting over the end of the block 249 so as to prevent the latter from again yielding upwardly until the crosshead is approaching the end of the next driving stroke. 10 This is accomplished by a projecting finger 254 secured to the top of the crosshead casting 66, engaging against a lug 255 on the latching bar 252, just after the roller 247 has passed the pivot 251. When the crosshead reaches retracted position, the latching bar 252 is moved to inoperative position by the engagement of the finger 254 with a lug 256 on the other end of the bar.

By freeing the roll from the pad 84 just prior to the end of the driving stroke of the crosshead, the roll is allowed to continue freely rotating under the momentum imparted to it by the starting impulse and under the pull of the web as the same is drawn into the press.

Reviewing the operation of the device, the normal operating position of the roll 31 is a little above that shown in dotted lines in Fig. 1. As said roll 31 nears exhaustion, the operator, having previously applied adhesive to the roll 32, moves the reel a little so as to bring said roll 32 as near as possible to the web 38 without touching the same, this position being shown in dotted lines in Fig. 1. In the normal operating position, the crosshead 63, fully advanced, obstructs manipulation of the valve 174 as previously stated. In the temporary position shown in dotted lines, the crosshead has been moved sufficiently to free the valve 174 for manual operation. The operator may then, if he wishes, lock the pad 84 against the roll 32 to prevent the latter from rotating out of position, while he watches the roll 31 to determine when to start the paster operation. He may also release the pad 84 so as to reset the position of the adhesive coated area on the roll preparatory to starting the paster operation, this being done by turning the roll by hand. When he decides the roll 31 has been sufficiently exhausted, he closes the switch that starts the reel rotating to carry roll 32 into the web.

As the crosshead is thus retracted by the engagement of the operating finger 197 with the arm 208 of the crosshead assembly, the projection 235 will move the trigger 227 to the left, operating valve 174 so that if the pad 84 has not already been locked against the roll 32, it will be locked automatically. As the reel continues to rotate, the roll 32 will contact the web 38 and bow it outwardly, the web sliding against the smooth rounded surface of the roll, but not rotating the roll since it is held against rotation by the pad 84. When the reel nears the full-line position shown in Fig. 1, the finger 197 will release the arm 208 and shortly thereafter will engage the trigger finger 203 and cause the valve 165 to be operated so as to admit air to the cylinder 64 of the pneumatic drive unit, resulting in the crosshead 63 being forcibly driven to the right. The roll engaging unit, being locked against the end of the roll, will move the roll in unison with the movement of the crosshead, the arm 77 swinging first upwardly, then downwardly so as to allow the pad 84 to follow the arc of movement of the region of the roll against which it is engaged. As the crosshead

5 nears the end of its driving stroke, the valve 122 will be operated to release the air from the cylinder 81, thus releasing the pad 84 from engagement with the roll 32 and allowing the latter to continue rotation under the momentum it has acquired. The region of adhesive coated surface 239, which was positioned at the top of the roll at the commencement of the starting impulse, will move around the roll in a clockwise direction until it contacts the web 38, whereupon it will adhere to the latter under the pressure of the brushes 51.

10 The engagement of the web 38 against the roll 32 assists in bringing the roll up to speed, said web being effective, after the drive unit has released the roll, to adjust the speed of the roll to its own speed before the adhesion takes place. This minimizes the likelihood of failure of adhesion.

15 20 Bleeding of the main cylinder 64 as the driving stroke is completed, is accomplished by the moving of the trigger 227 to the right by the projections 234 and 235, causing the rod 217, through the medium of a collar 257 (Fig. 13), which, near the end of the driving stroke, engages the collar 201 on the rod 185, to move said rod to the right, as viewed in Fig. 13, thereby operating the valve 165 to release the air from said cylinder 64. The collars 257 and 201 will be 25 in engagement when the parts are in the relative positions shown in Fig. 15, so that the rod 185 will be locked against movement by the locking of the rod 217, and valve 165 as well as valve 174 will be rendered inoperative.

30 35 The foregoing detailed description has been given for clearness of understanding only, and no unnecessary limitations should be understood therefrom, but the appended claims should be construed as broadly as permissible in view of the prior art.

40 45 What I regard as new and desire to secure by Letters Patent is:

1. In a roll changing apparatus for printing presses, a movable support for a plurality of web rolls, means for bringing into engagement a new roll and the web of the roll that is feeding the press, a roll start-up device including a member adapted to engage an end of the new roll in a plane at right angles to its axis and to move in fixed engagement therewith for a short distance, means for moving said member into engagement with the roll, and means for actuating said roll engaging member to cause the same to impart a quick rotative impulse to the roll preparatory to making a paster between the webs of the expiring and new rolls.

50 55 60 65 70 75 2. In a roll changing apparatus for printing presses, a movable support for a plurality of web rolls, means for bringing into engagement a new roll and the web of the roll that is feeding the press, a roll start-up device including a member adapted to engage an end of the new roll in a plane at right angles to its axis and to move in fixed engagement therewith for a short distance, means for moving said member into engagement with the roll, and means operated by movement of the roll support for actuating said roll engaging member to cause the same to impart a quick rotative impulse to the roll preparatory to making a paster between the webs of the expiring and new rolls.

3. In a roll changing apparatus for printing presses, a movable support for a plurality of web rolls, means for bringing into engagement a new roll and the web of the roll that is feeding the

press, a roll start-up device including a member adapted to engage an end of the new roll, means for moving said member into engagement with the roll, means whereby said roll engaging member may be held in engagement with the roll to prevent rotation thereof while the same is being moved into engagement with the running web, and means for actuating said roll engaging member to cause the same to impart a quick rotative impulse preparatory to making a paster between the webs of the expiring and new rolls.

4. In a roll changing apparatus for printing presses, a movable support for a plurality of web rolls, means for bringing into engagement a new roll and the web of the roll that is feeding the press, and a pneumatically operated device operable to impart a rotative impulse to the new roll while the latter is in engagement with said running web preparatory to making a paster between the webs of the new and old rolls, said device including a driving member engageable with said new roll prior to a driving stroke of said member and automatically acting means for causing said member to move out of driving engagement with said roll upon completion of said stroke.

5. In a roll changing apparatus for printing presses, a movable support for a plurality of web rolls, means for bringing into engagement a new roll and the web of the roll that is feeding the press, a pneumatically operated device operable to impart a rotative impulse to the new roll while the latter is in engagement with said running web preparatory to making a paster between the webs of the new and old rolls in a plane at right angles to its axis, and means carried by said movable roll support for operating said pneumatic device.

6. In a roll changing apparatus for printing presses, a movable support for a plurality of web rolls, means for bringing into engagement a new roll and the web of the roll that is feeding the press, a roll start-up device including a member adapted to engage an end of the new roll in a plane at right angles to its axis and to move in fixed engagement therewith for a short distance, means for moving said member into engagement with the roll, and means for actuating said roll engaging member to cause the same to impart a quick rotative impulse to the roll within less than one revolution thereof preparatory to making a paster between the webs of the expiring and new rolls.

7. In a roll changing apparatus for printing presses, a movable support for a plurality of web rolls, means for bringing into engagement a new roll and the web of the roll that is feeding the press, reciprocable roll engaging means, means carried by the roll support for retracting said engaging means during such movement of the new roll into the web, and driving means adapted to return said engaging means from retracted to advanced position and to thereby impart a rotative impulse to the new roll preparatory to making a paster between the webs of the new and old rolls.

8. In a roll changing apparatus for printing presses, a movable support for a plurality of web rolls, means for bringing into engagement a new roll and the web of the roll that is feeding the press, reciprocable roll engaging means, means carried by the roll support for retracting said engaging means during such movement of the new roll into the web, and pneumatic driving means controlled by said retracting means when

the engaging means reaches retracted position, for returning said engaging means to advanced position and thereby imparting a rotative impulse to the roll preparatory to making a paster between the web of the new and old rolls.

9. In a roll changing apparatus for printing presses, a movable support for a plurality of web rolls, means for moving said support to carry a new roll into engagement with the web of the roll that is feeding the press, roll engaging means, pneumatic driving means for imparting a rotative impulse at right angles to the axis of the new roll through the medium of said engaging means, a valve for controlling the admission of a driving fluid to said pneumatic means, and means carried by the roll support for operating said valve to admit fluid to the pneumatic means and thereby actuate said roll engaging means to impart said rotative impulse to the new roll after the latter has reached a predetermined position in engagement with the web.

10. In a roll changing apparatus for printing presses, a movable support for a plurality of web rolls, means for moving said support to carry a new roll into engagement with the web of the roll that is feeding the press, driving means including a reciprocable member having an operative stroke in engagement with said new roll and a return stroke out of engagement therewith for imparting a rotative impulse to the new roll, and means carried by the roll support for initiating the action of said driving means when the roll has reached a predetermined position in engagement with the web.

11. In a roll changing apparatus for printing presses, a movable support for a plurality of web rolls, means for moving said support to carry a new roll into engagement with the web of the roll that is feeding the press, pneumatic roll engaging means, a valve to control the flow of fluid to said engaging means, means adapted to automatically operate said valve to admit fluid to said engaging means as a result of such movement of the new roll into engagement with the web, and driving means acting through the medium of said engaging means to impart a rotative impulse at right angles to the axis of the new roll when the latter has reached a predetermined position in engagement with the web.

12. In a roll changing apparatus for printing presses, a movable support for a plurality of web rolls, means for moving said support to carry a new roll into engagement with the web of the roll that is feeding the press, pneumatic roll engaging means, a valve to control the admission of fluid to said engaging means, a valve to control the release of fluid from said engaging means, manual means for operating said admission valve, driving means acting through the medium of said engaging means to impart a rotative impulse to the new roll when the latter has reached a predetermined position in engagement with the web, and means for automatically operating said release valve when said driving means is nearing the end of its driving stroke.

13. In a roll changing apparatus for printing presses, a movable support for a plurality of web rolls, means for moving said support to carry a new roll into engagement with the web of the roll that is feeding the press, pneumatic roll engaging means, a valve to control the release of fluid from said engaging means, driving means acting through the medium of said engaging means, for imparting a rotative impulse to the new roll, and means controlled by the movement of said en-

gaging means for automatically operating said release valve shortly prior to the end of the driving stroke for releasing said engaging means from its engagement with the roll.

14. In a roll changing apparatus for printing presses, a movable support for a plurality of web rolls, means for bringing into engagement a new roll and the web of the roll that is feeding the press, roll engaging means, driving means acting through the medium of said engaging means for imparting a rotative impulse to the new roll, and means controlled by the movement of said engaging means for releasing the same from engagement with the roll shortly prior to the end of the driving stroke.

15. In a roll changing apparatus for printing presses, a movable support for a plurality of web rolls, means for bringing into engagement a new roll and the web of the roll that is feeding the press, a roll start-up device including a member adapted to engage an end of the new roll, means for moving said member into engagement with the roll, means for actuating said roll engaging member to cause the same to impart a quick rotative impulse to the roll preparatory to making a paster between the webs of the expiring and new rolls, and means for causing immediate disengagement of said roll engaging member with the roll at the end of the operative stroke of said actuating means.

16. In a roll changing apparatus for printing presses, a movable support for a plurality of web rolls, means for bringing into engagement a new roll and the web of the roll that is feeding the press, a roll start-up device including a member adapted to engage an end of the new roll, means for moving said member into engagement with the roll, means for actuating said roll engaging member to cause the same to impart a quick rotative impulse to the roll preparatory to making a paster between the webs of the expiring and new rolls, means for causing immediate disen-

gagement of said roll engaging member with the roll at the end of the operative stroke of said actuating means, and means for rendering inoperative said means for moving said roll engaging member into engagement with the roll while the parts are in their normal position of rest.

17. In a roll changing apparatus for printing presses, a movable support for a plurality of web rolls, means for bringing into engagement a new roll and the web of the roll that is feeding the press, a roll start-up device including a member adapted to engage an end of the new roll, a pivotally mounted support on which said roll engaging member is carried, means for moving said roll engaging member into contact with the roll and means for actuating the roll engaging unit to cause the same to impart a quick rotative impulse to the roll preparatory to making a paster between the webs of the expiring and new rolls, said support being movable on its pivot to permit said roll engaging member to maintain contact with the point on the roll engaged thereby throughout the arc of movement thereof while such engagement is maintained.

18. In a roll changing apparatus for printing presses, a movable support for a plurality of web rolls, means for bringing into engagement a new roll and the web of the roll that is feeding the press, a roll start-up device including a member adapted to engage an end of the new roll in a plane at right angles to its axis and to move in fixed engagement therewith for a short distance, means for moving said member into engagement with the roll, means for actuating said roll engaging member to cause the same to impart a quick rotative impulse to the roll preparatory to making a paster between the webs of the expiring and new rolls, and means for causing immediate disengagement of said roll engaging member with the roll at the end of the operative stroke of said actuating means.

ALLAN J. CLINE.
